US00D967814S

(12) **United States Design Patent** (10) **Patent No.:** **US D967,814 S**
(45) **Date of Patent:** **** Oct. 25, 2022**

(54) **COMPUTING DEVICE**

(71) Applicant: **Microsoft Corporation**, Redmond, WA (US)

(72) Inventors: **Timothy G. Escolin**, Seattle, WA (US); **Young Soo Kim**, Bellevue, WA (US); **Scott Schenone**, Seattle, WA (US); **Panos Costa Panay**, Redmond, WA (US); **Ralf Groene**, Kirkland, WA (US); **Byungkwan Min**, Kirkland, WA (US)

(73) Assignee: **Microsoft Corporation**, Redmond, WA (US)

(**) Term: **15 Years**

(21) Appl. No.: **29/707,914**

(22) Filed: **Oct. 1, 2019**

(51) LOC (13) Cl. **14-02**

(52) U.S. Cl.

USPC **D14/315**

(58) **Field of Classification Search**

USPC D14/315, 323, 341, 371, 376, 432–433, D14/439; D8/306, 321, 323, 325, 329; D20/43

CPC B41J 5/00; B41J 5/10; B41J 5/12; E05D 3/00; E05D 3/02; E05D 3/04

(57) **CLAIM**

The ornamental design for a computing device, as shown and described.

DESCRIPTION

FIG. 1 is a perspective view of a computing device showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depicting features of the computing device in FIGS. 1 and 6 form no part of the claimed design.

1 Claim, 5 Drawing Sheets
